UNITED STATES PATENT OFFICE.

EDWARD CRAIG, OF ST. JOSEPH, MICHIGAN, ASSIGNOR TO SARANAC MACHINE CO., OF ST. JOSEPH, MICHIGAN, A CORPORATION OF MICHIGAN.

CLIMAX-BASKET MACHINE.

1,192,041.

Specification of Letters Patent. Patented July 25, 1916.

Application filed October 8, 1909. Serial No. 521,742.

To all whom it may concern:

Be it known that I, EDWARD CRAIG, a citizen of the United States of America, and resident of St. Joseph, Berrien county, 5 Michigan, have invented a certain new and useful Improvement in Climax-Basket Machines, of which the following is a specification.

My invention contemplates an improvement 10 in machinery for making baskets, and more particularly machines for making baskets of the kind commonly known as "Climax" baskets, which are oblong in form and used very extensively for shipping peaches 15 and grapes and other kinds of fruit.

Generally stated, the object of my invention is to provide an improved machine which will render more satisfactory in various ways the manufacture of baskets of 20 this kind.

It is also an object to provide certain details and features of construction and combinations tending to increase the general efficiency of a machine of this particular 25 character.

To the foregoing and other useful ends, my invention consists in matters hereinafter set forth and claimed.

In the accompanying drawings—Figure 1 30 is a side elevation of a basket or stapling machine embodying the principles of my invention, showing the basket form in section. Fig. 2 is a horizontal section on line 2—2 in Fig. 1. Fig. 3 is a detail section on line 35 3—3 in Fig. 1. Fig. 4 is a detail section on line 4—4 in Fig. 1. Fig. 5 is an enlarged and fragmentary side elevation of the stapling mechanism, showing the bottom clamp and the staple driver take-up lever. Fig. 6 40 is an end elevation of the mechanism shown in Fig. 5. Fig. 7 is a detail horizontal section on line 7—7 in Fig. 5. Fig. 8 is a detail fragmentary view of the pivoted connection of the bottom clamp.

As thus illustrated, my invention 45 comprises a body A upon which are mounted the various operative parts. A shaft B is supported in bearings on said body. This shaft has a crank C that operates a pitman 50 D. Said pitman operates a vertically reciprocating rod E. At its upper end this rod carries the upper stapling or driving head F. This stapling head, which is in the form of a casting, operates the usual staple drivers 55 f and the staple formers f'. The said staple

formers and drivers slide up and down in guides or housings provided on the lower or cross head G, which latter is also a casting. This lower head G is secured to the upper end of a bar g that slides up and down in a 60 groove g' in the body. In this way the lower head G slides on the rod E. The lower end of the rod E has a horizontal portion e that connects with the pitman D, and which acts as a shoulder to engage the lower 65 end of the bar g, when the two heads rise. In this way the upper head F travels upward a distance without moving the head G, and then when the portion e strikes the lower end of the bar g the head G moves upward 70 the desired distance. This gives clearance below the head G and facilitates the manipulation of the materials from which the baskets are made.

The staplers may be of any suitable form 75 or character. The drivers are yieldingly actuated by reason of their engagement with the levers H pivoted on the head F. These levers each have a cam portion or heel h that bears upon the upper end of the driver f. 80 The outer end of each lever is yieldingly held against rising by the spring h'. These springs are strong enough to enable the driver to properly insert the staples. If the stock varies in thickness, the springs h' enable 85 the drivers to insert the staples properly and without damaging the stock. If the lower ends of the drivers f strike the stock before the head F stops moving downward, then the springs h' yield and allow the 90 drivers to remain stationary while the head completes its downward stroke. These elements H are, therefore, called driver-take-up levers. Rods f² are secured to the staple take-up levers. Rods f² are secured to the staple formers f' and are provided with springs 95 f³ by which said formers are held down on the work after being unlocked from the devices in the usual and well known manner.

The form I is mounted on the front of the machine and disposed below the staplers. 100 This form may have any desired shape. As shown, it is of the kind necessary for making what are commonly known as "Climax" baskets. In this way it is easily manipulated by the operator. The stud or axle J is inclined slightly upward at its outer end, so as to bring the upper surface of the form into a horizontal position. This stud J has a rotatable sleeve j that works in the slot i of the form. Thus the form I can be shifted 105 110

longitudinally and turned around on the stud or axle to bring the different sides of the basket successively into position for stapling. The sleeve j can rotate on the 5 stud, and thus the form is more easily shifted. The form is held on the stud by a cap plate j' . A guide j^2 on the body A engages the hub j^3 of the form to keep the same level while traveling endwise. When the 10 end of the slot i is reached by the stud, the guide j^2 permits the form to be turned over and then shifted endwise in the opposite direction. While the basket is being stapled, it is held on the form by a clamp K pivoted 15 on the head G. This clamp has a cam-shaped upper end k that is engaged by an adjustable cam k' on the head F. When the said head moves down, it actuates the clamp K and causes the lower end k^2 thereof to engage the bottom of the basket. A spring k^3 also serves to hold the said clamp in engagement with the basket. The clamp has a notch k^4 that engages the pivot k^5 , and is 20 yieldingly held thereon by the flat spring k^6 . This spring k^6 is secured at its upper 25 end to the clamp K, and the free lower end thereof covers the notch k^4 and engages the pivot k^5 . In this way the spring k^6 will yield if the stock is too thick, and thus 30 breakage is avoided. With uniform stock, however, the clamp will work without this flat spring. The cam k' can be rotated or 35 adjusted to vary the stroke of the clamp. Thus the mechanism is adjustable for different kinds of thicknesses of stock. The spring controlled member K' engages the clamp K to hold the same in engagement with the cam k' . This member slides endwise and horizontally in the head G.

40 The guides L serve to direct the strips or hoops onto the basket as the form moves sidewise or turns around. These guides are on an arm l that is secured to the body of the machine.

45 The wire feeding devices M for the staplers may be of any suitable form. They are mounted on the lower head G, and travel up and down with the latter. Each feed device has a ratchet wheel m engaged by the pawl 50 m' carried by the head F, whereby the feed devices M are actuated to feed the wire when the heads move downward. Thus two staples are driven each time the head moves down. One staple is inserted in the rim of 55 the basket and the other in the bottom.

Thus it will be seen that I provide an improved and highly efficient machine for making baskets or other articles. I claim the different features both broadly and specifically, as well as the various combinations, and do not limit myself to any particular use for the machine, or to the exact construction shown and described.

What I claim as my invention is:

65 1. In a staple driving mechanism, a re-

ciprocating driving head, means for operating said head, a reciprocating cross-head actuated by the means for operating the driving head, wire feeding mechanism carried by the cross-head, actuating means for the wire feeding mechanism operated by the driving head, and staple forming and driving mechanisms working in guides carried by the cross-head and having actuating connections with the driving head; substantially 75 as described.

2. In a staple driving mechanism, a cross-head having wire feeding mechanism connected thereto, a reciprocating staple former 80 slidably mounted on the cross-head, a reciprocating staple driver also slidably mounted on the cross-head, a reciprocating driving head, connections arranged for operating the driving head and having means arranged to give the cross-head a limited vertical movement on the down and up strokes of the driving head, means connected to the driving head for actuating the wire feeding mechanism, and actuating connections between the staple former and driver and the 90 driving head; substantially as described.

3. In staple driving mechanism, a vertically movable cross-head, having wire feeding mechanism connected thereto, guides or housings secured thereto, staple forming 95 and driving devices mounted in said housings, a vertically movable driving head, elements forming a connection between the driving head and the cross-head, means for operating said elements to actuate both 100 heads upwardly, connections between the wire feeding mechanism and the driving head, and independent actuating connections between the driving head and the staple-forming and driving devices; substantially 105 as described.

4. In staple driving mechanism, a cross-head having a guide or housing, a wire feeding device carried by the cross-head, a staple driver mounted to reciprocate in the housing, a staple former also mounted to reciprocate in said housing, a vertically movable driving head, actuating connections between the driving head and the wire feeding mechanism, independent actuating connections 110 between the driving head and the staple driver and the staple former, and a connection between the driving head and the cross-head through which both heads may be operated; substantially as described.

5. In staple driving mechanism, a reciprocating driving head, means for operating said head, a reciprocating cross-head actuated by the operations of the means for operating the driving head, wire feeding 125 mechanism carried by the cross-head, actuating means for the wire feeding mechanism operated by the driving head, staple forming and driving mechanisms working in guides carried by the cross-head and having 130

actuating connections with the driving head, a work clamp carried by the cross-head, and means mounted on the driving head for operating said clamp.

- 5 6. A stapling machine comprising a driving head and a cross head provided with staple forming and driving devices, means for operating the driving head, a form disposed under the cross-head, provided with a
10 longitudinal slot, a support in said slot, a work clamp pivoted on the cross-head, and means mounted on the driving head for operating said clamp.
7. A stapling machine comprising a driving head and a cross head provided with staple forming and driving devices, means for operating the driving head, a form disposed under the cross-head, provided with a longitudinal slot, a support in said slot, a
15 work clamp pivoted on the cross-head, means mounted on the driving head for operating said clamp, and a spring applied to the pivot of said clamp for producing a yielding clamping action thereof.
- 20 8. A stapling machine comprising a driving head and a cross head provided with staple forming and driving devices, means

for operating the driving head, a form disposed under the cross-head, means operated by the driving head to clamp the bottom of the basket against the form, said form being provided with a longitudinal slot, a support in said slot, said devices including a staple driver, a cam pivoted on the driving head, engaging the upper end of said staple driver, and a spring for yieldingly holding said cam in operative position.

9. A stapling machine comprising a driving head and a cross head provided with staple forming and driving devices, means for operating the driving head, a form disposed under the cross-head, means operated by the driving head to clamp the bottom of the basket against the form, said form being provided with a longitudinal slot, a support in said slot, and means for operating said driving head, having provisions for varying the distance between said heads.

Signed by me at St. Joseph, Michigan,
this 20th day of September 1909.

EDWARD CRAIG.
